(57) **ABSTRACT**

A controllable, multi-zone control system is provided for controlling the inflow of fluids into a completion, e.g. a lateral completion, at a plurality of well zones. According to an embodiment, flow control devices are distributed along the completion and a control module is positioned between the flow control devices, e.g. in a middle region of the completion. The control module is supplied with hydraulic actuating fluid and is electrically controllable to enable selective distribution of the hydraulic actuating fluid to selected flow control devices. The control module may be controlled via electric signals, thus controlling distribution of hydraulic actuating fluid under pressure to selected flow control devices so as to shift the selected flow control devices to a desired open or closed flow position.

**ACTIVE FLOW CONTROL WITH
MULTIZONE HYDRAULIC POWER
DISTRIBUTION MODULE**

BACKGROUND

Open hole horizontal completions have been used in the oil and gas industry for hydrocarbon extraction in both sandstone and carbonate formations. To combat early well failure due to sand screen plugging or sand breakthrough, completions have been combined with gravel packs to filter out the sand. Additionally, a lower completion string often is combined with an upper completion string via a connect-disconnect system. The upper completion string may be combined with an electric submersible pumping system, and this configuration allows operators to change out the electric submersible pumping system during maintenance. The electric submersible pumping system is used to produce well fluids which flow from the surrounding formation into the lower completion. However, obtaining a desired level of control over the inflow of fluids with respect to a plurality of zones along a horizontal wellbore has been difficult.

SUMMARY

In general, a system and methodology provide a multi-zone control system for controlling the inflow of fluids into a completion, e.g. a lateral completion, at a plurality of well zones. According to an embodiment, flow control devices are distributed along the completion and a control module is positioned between the flow control devices, e.g. in a middle region of the completion. The control module is supplied with hydraulic actuating fluid and is electrically controllable to enable selective distribution of the hydraulic actuating fluid to specific flow control devices. The control module may be actuated via electric signals, thus controlling distribution of hydraulic actuating fluid under pressure to selected flow control devices so as to shift the selected flow control devices to a desired open or closed flow position.

However, many modifications are possible without materially departing from the teachings of this disclosure. Accordingly, such modifications are intended to be included within the scope of this disclosure as defined in the claims.

BRIEF DESCRIPTION OF THE DRAWINGS

Certain embodiments of the disclosure will hereafter be described with reference to the accompanying drawings, wherein like reference numerals denote like elements. It should be understood, however, that the accompanying figures illustrate the various implementations described herein and are not meant to limit the scope of various technologies described herein, and:

FIG. 1 is an illustration of an example of a completion deployed in a lateral wellbore and combined with a multi-zone control system, according to an embodiment of the disclosure;

FIG. 2 is a schematic illustration of an example of a multi-zone control system utilizing a control module combined with a plurality of flow control devices, according to an embodiment of the disclosure;

FIG. 3 is a schematic illustration of another example of a multi-zone control system utilizing a control module combined with a plurality of flow control devices, according to an embodiment of the disclosure; and

2

FIG. 4 is a schematic illustration of an example of lateral completion arrangement for use with a multi-zone control system, according to an embodiment of the disclosure.

DETAILED DESCRIPTION

In the following description, numerous details are set forth to provide an understanding of some embodiments of the present disclosure. However, it will be understood by those of ordinary skill in the art that the system and/or methodology may be practiced without these details and that numerous variations or modifications from the described embodiments may be possible.

The present disclosure generally relates to an electrically controllable, multi-zone control system. The multi-zone control system may be used for controlling the inflow of fluids into a completion, e.g. a lateral completion, at a plurality of well zones. According to an embodiment, hydraulically actuated, flow control devices are distributed along the completion in the various well zones. Additionally, a control module is positioned between the flow control devices, e.g. in a middle region of the completion. For example, the control module may be positioned between well zones and operated downhole for controlling flow control devices uphole and downhole relative to the location of the control module.

The control module is supplied with hydraulic actuating fluid from a source, such as a downhole hydraulic fluid source or a surface source. In operation, the control module is electrically controllable to enable selective distribution of the hydraulic actuating fluid to specific flow control devices, e.g. flow control devices in a specific well zone. The control module may be actuated via electric signals to provide controlled distribution of hydraulic actuating fluid under pressure to selected flow control devices. The hydraulic actuating fluid is used to shift the selected flow control devices to a desired open or closed flow position allowing or blocking flow from the surrounding well zone.

Effectively, the control module serves as a multi-zone distribution hub. In some embodiments, the control module is supplied with hydraulic actuating fluid via a single hydraulic control line and a pump is used to place the actuating fluid under suitable pressure for actuating the flow control devices. An electric line may be routed downhole to the control module to provide electrical control signals to the control module. Based on those control signals, the control module is actuated to direct hydraulic actuating fluid through relatively short hydraulic lines to specific flow control devices. As a result, electrical signals supplied through, for example, a single electric line may be routed downhole and used to ultimately control operation of flow control devices in a plurality of well zones, e.g. 2-5 well zones. Use of the electric line enables and simplifies active surface control of fluid flow into the completion at a plurality of downhole well zones. The use of electrical control signals also enhances the ability to multi-drop such a system to various other well zones.

Referring generally to FIG. 1, an embodiment of a well system 20 is illustrated. In this embodiment, well system 20 is deployed in a wellbore 22 having a lateral wellbore section 24, e.g. a generally horizontal wellbore section. The well system 20 comprises a completion 26 deployed in wellbore 22. In a variety of applications, completion 26 may be in the form of a lateral completion deployed in lateral wellbore section 24 along a plurality of well zones 28.

In some applications, the lateral completion 26 is a lower completion initially installed downhole and then coupled

with an upper completion **30** (shown in dashed lines) via a connect-disconnect system **32**. An artificial lift system, e.g. an electric submersible pumping system, may be deployed as part of or in cooperation with the upper completion **30** to produce fluids received via lateral completion **26**. During a production operation, the lateral wellbore section **24** may be isolated via a packer **34**, such as a production packer, set against a surrounding casing **35**.

Lateral completion **26** comprises an interior flow region or passage **36** which may be along the interior of a base pipe **38**. The lateral completion **26** also comprises a plurality of sand screens **40** disposed about the base pipe **38** and located in corresponding well zones **28**. Additionally, the lateral completion **26** comprises a plurality of flow control device systems **41**. Each flow control device system **41** may comprise a plurality of flow control devices **42** located in each well zone **28**, as further illustrated in FIG. 2. In a variety of applications, the lateral completion **26** is assembled by connecting sections which may be referred to as joints **43**. For example, sand screen assembly joints **43** may be sequentially joined and deployed along lateral wellbore **24**.

Referring generally to FIGS. 1 and 2, the flow control devices **42** are uniquely controlled via a control module **44**. The control module **44** effectively enables control of fluid flow from an exterior of lateral completion **26** to an interior of lateral completion **26** at specifically selected well zones **28**. In a variety of applications, the control module **44** may be located between sand screens **40** and between well zones **28**, e.g. at a generally central or middle location with respect to the plurality of well zones **28**. In other words, the control module **44** may be positioned such that at least some of the flow control devices **42** are uphole and at least some of the flow control devices **42** are downhole relative to the location of the control module **44**. It should be noted uphole refers to the side of the module **44** toward the surface regardless of whether the lateral wellbore **24** is horizontal or inclined. The downhole side of control module **44** is the opposite side which is farther into the wellbore relative to the control module. The well zones **28** may be separated and isolated via isolation packers **46** which are deployed in an un-set state and then set against the surrounding open hole wellbore wall, as illustrated.

To facilitate an initial gravel packing of lateral wellbore **24** after setting of the packers **46**, the completion **26** also may comprise a plurality of shunt tubes **48** which deliver the gravel packing slurry to sequential well zones **28**. The shunt tubes extending through sequential well zones **28** may be joined at a shunt tube isolation valve structure **50** having valves for controlling the flow of gravel slurry. The valves in valve structure **50** serve to further isolate adjacent well zones **28** when the valves are closed, e.g. closed after gravel packing. During a gravel packing operation, gravel packing slurry is delivered downhole by a service tool and then diverted from the inside diameter to the annulus surrounding completion **26** via a port closure sleeve **52**. The gravel slurry flows along the annulus and shunt tubes **48** to form a uniform gravel pack **54**.

In an operational example, the gravel slurry begins packing from the heel of the well and as the gravel/sand settles the dehydration fluid travels along a drainage layer between the first sand screen **40** and a solid section of the base pipe **38**. The dehydration fluid travels along this fluid return path until reaching a first sliding sleeve **56** of a plurality of sliding sleeves. In some applications, some of the returning dehydration fluid also flows through the corresponding flow control device system **41**, thus reducing or removing the use of additional sliding sleeves **56**. The dehydration fluid then

flows into interior **36** and back to the surface through the base pipe **38** and corresponding tubing. Upon completion of the heel zone, the gravel slurry pumping operation is continued and this process is repeated at subsequent well zones **28**, with the aid of shunt tubes **48**, until screen out pressure is reached and the pumps are stopped.

Once the service tool is retrieved, the upper completion **30** is deployed downhole and engaged with the lower completion **26** to establish communication from the surface to the lower completion **26**. For example, electrical and/or hydraulic communication may be established through the connect-disconnect **32** which can be in the form of an electrically powered connect-disconnect system. Electrical power and electrical control signals may be provided to the control module **44** via an electric line **58** routed through the connect-disconnect **32**. The electric line **58** may be coupled with a control system **60**, e.g. a computer-based control system, located at the surface or at another suitable location.

In some applications, hydraulic actuating fluid may be provided to control module **44** via a hydraulic line **62** to enable selective actuation of the flow control devices **42**. The hydraulic line **62** may similarly be routed through the connect-disconnect **32** and coupled with a hydraulic pump and control system **64** located at the surface or at another suitable location. In other embodiments, however, the hydraulic line **62** may be routed to control module **44** from a downhole fluid reservoir as described in greater detail below.

It should be noted the electric line **58** may comprise a single or multiple conductive paths for carrying electrical power, control signals, and/or data signals, e.g. data signals from sensors or other downhole equipment. By way of example, the electric line **58** may be in the form of a single line having a plurality of conductors able to independently carry power and/or data signals between, for example, surface control **60** and control module **44**. Similarly, the hydraulic line **62** may comprise a single flow path or a plurality of flow paths for carrying hydraulic actuation fluid.

Referring again to FIG. 2, a schematic illustration is provided of an embodiment of an overall multi-zone control system **66** in which the control module **44** is electrically controlled via electrical control line **58** and serves as a multi-zone distribution hub. In this embodiment, sequential well zones **28** are isolated via packers **46** and the control module **44** is located proximate a generally central well zone **28**. The control module **44** may comprise control electronics **68**, e.g. a controller, which receive electrical control signals via electric line **58**. The electronics **68** may comprise control and telemetry features, and it may be embodied in a printed circuit board or otherwise suitably configured in control module **44**.

Based on the control signals received via electric line **58**, the controller **68** executes flow control according to the instructions carried by the control signals. For example, the controller **68** may be used to control operation of a hydraulic manifold **70** of control module **44**. As described in greater detail below, the hydraulic manifold **70** may comprise a variety of electrically controllable valves which are actuated according to instructions carried by the electrical control signals. The control module **44**/manifold **70** are thus selectively controlled to direct flows of actuating fluid to the appropriate flow control system **41** and corresponding control devices **42** via a corresponding hydraulic line or lines **72**.

In some embodiments, each hydraulic line **72** is routed to a corresponding well zone **28** and controls the simultaneous opening or closing of the group of flow control devices **42**.

in that specific corresponding well zone 28. For example, control instructions may be provided by control system 60 to controller 68 of control module 44 via appropriate electrical signals sent along electric line 58. In response to those instructions, the control module 44 controls hydraulic manifold 70 to ensure a flow of hydraulic actuating fluid to the appropriate flow control devices 42 in a given well zone or zones 28. Accordingly, if undesirable fluid, e.g. water or undesirable gas, begins to flow into the interior 36 of lateral completion 26 at a specific well zone 28, the group of flow control devices 42 in that particular well zone 28 may be closed to block further inflow.

Depending on the type of surrounding formation and equipment used to construct lower completion 26, the number and length of well zones 28 may vary. By way of example, the well zones 28 may be approximately 1000 feet in length and control module 44 may be used to control 2-5 well zones 28. However, the lengths of well zones 28 may range from a few feet to thousands of feet, and the length may be the same or dissimilar from one well zone 28 to the next. Accordingly, the number of flow control devices 42 placed in each well zone 28 also may vary according to the parameters of a given application.

In the specific example illustrated, the overall multi-zone control system 66 employs control module 44 to control well fluid flow at five different well zones 28. Sometimes the number of well zones 28 controlled by an individual control module 44 may be selected based on the number of control line feed throughs available at isolation packers 46. For example, if the isolation packers 46 have three control line feed throughs, then the number of well zones 28 serviced by the control module 44 may be selected based on the ability to accommodate the single electrical line 58 and a pair of hydraulic lines 72. If the number of feed throughs in isolation packers 46 is increased, however, the multidrop to other well zones 28 can also be increased accordingly. Also, the electric line 58 may be routed to additional control modules 44 so as to enable further control over inflow of well fluids at additional well zones 28.

Referring generally to FIG. 3, another embodiment of multi-zone control system 66 is illustrated. In this example, the control module 44 is supplied with hydraulic actuating fluid from a downhole reservoir 74 which may be pressure compensated via one or more compensators 76. For example, the downhole reservoir 74 may serve as a hydraulic fluid bank for storing hydraulic actuating fluid downhole in a closed loop while being reservoir pressure or tubing pressure compensated via compensators 76.

The downhole reservoir 74 supplies hydraulic actuating fluid to control module 44 via hydraulic line 62. In the embodiment illustrated, control module 44 comprises a hydraulic pump 78 powered by a motor 80 which, in turn, may be coupled to electrical power via electric line 58. In some embodiments, the hydraulic pump 78 and the motor 80 may be combined into a single component. In the illustrated example, the hydraulic manifold 70 works in cooperation with a plurality of electrically actuated valves 82, e.g. solenoid operated valves, to control flow of hydraulic actuating fluid along hydraulic lines 72. An additional electrically actuated valve 84 may be used to enable circulation of hydraulic actuating fluid back to reservoir 74 when the electrically actuated valves 82 are closed to flow. This allows hydraulic pump 78 to continually operate and to simply return the pumped actuating fluid back to reservoir 74 when the electrically actuated valves 82 are in the closed position.

When the control module 44, e.g. controller 68, receives instructions to change the flow position of flow control devices 42 in a given well zone or zones 28, the appropriate valves 82 are shifted electrically to the desired flow or no-flow position. In the embodiment illustrated, the electrically actuated valve 84 has been shifted to the closed or no-flow position and one of the electrically controlled valves 82 has been shifted to the open flow position to enable flow of actuating fluid to the corresponding flow control devices 42. In the illustrated example, the valve 82 shifted to the open flow position has effectively directed actuating fluid under pressure to the flow control devices 42 in the middle well zone 28, thus shifting those flow control devices 42 to the closed flow position. When flow control devices 42 in the middle well zone 28 are closed, well fluids are prevented from flowing from the exterior of completion 26 to interior 36 at that well zone.

Depending on the application, flow control devices 42 may have a variety of configurations. By way of example, 20 the flow control devices 42 may comprise plunger assemblies 86, e.g. hydraulically actuated plungers 86. In some applications, the plungers 86 are spring biased or otherwise biased to an open flow position allowing flow of fluids from an exterior to an interior of lateral completion 26. When hydraulic actuating fluid is allowed to flow to specific hydraulically actuated plungers 86 via manifold 70, those plungers 86 are forced against the spring bias and into corresponding seats 88 to block further flow of fluids therethrough.

30 In some embodiments, individual electrically actuated valves 82 may be coupled with flow control devices 42 in more than one well zone 28. In the embodiment illustrated in FIG. 3, for example, one of the electrically actuated valves 82 controls corresponding flow control devices 42 in two well zones 28 on the left or heel side of control module 44. Another one of the electrically actuated valves 82 controls the remaining flow control devices 42 in those same two well zones 28. Depending on the parameters of a given well, formation, well zone arrangement, equipment configuration, and/or other factors, various flow control arrangements may be selected. In the illustrated example, two of the electrically actuated valves 82 are actuated to the open flow position to close the corresponding groups of flow control devices 42 and to completely block flow in each of the heel side well zones 28.

45 A sensor system 90 also may be used to optimize control over fluid flow in each of the well zones 28. By way of example, the sensor system 90 may comprise a plurality of sensors 92 positioned along completion 26 and/or at other suitable locations within well zones 28. The sensors 92 may be in the form of pressure sensors, temperature sensors, or other sensors distributed throughout the well zones 28. The sensor data, e.g. pressure and temperature data, may be sent along electric line 58 to at least one of the controller 68 or 50 control system 60 for processing. The processed data provides information that can be used for controlling flow into completion 26 at each well zone 28. For example, if the sensor data indicates the presence of water and/or gas, the flow control devices 42 for that well zone 28 may be closed 55 to block further inflow of fluid.

60 Depending on the reservoir and surrounding formation, the lateral completion 26 may be constructed in various lengths and configurations. In FIG. 4, a schematic illustration is provided in which the lateral completion 26 is structured with a plurality of screen assembly joints 43, e.g. four screen assembly joints, on each side of a flow control device, e.g. flow control device 42. Consequently, a given

flow control device(s) is able to collect fluid flow from the drainage layer in both uphole and downhole directions. For example, a given flow control device 42 may collect fluid flow from four uphole screen joints 43 and from four downhole screen joints. In the illustrated example, twenty four screen assembly joints 43 are disposed between the illustrated pair of isolation packers 46. Depending on the application, the number of joints 43 as well as a number of flow control devices 42 between isolation packers 46 may vary and may be selected based on, for example, zonal flow parameters. As described above, the inflow of well fluids is collected from the screens 40 and diverted along a drainage layer of the completion 26 to the flow control devices 42, e.g. to the plunger assemblies 86, to enable selective choking of production flow.

The overall zonal flow control system 66 may be adapted to a variety of applications and may be used to provide a low-cost, active control of multiple well zones 28, e.g. five well zones, from a single distribution hub/module 44. With additional feed throughs in packers 46 and in shunt tube isolation valve structures 50, additional well zones 28 may be controlled via module 44. The control module 44 serves as a distribution hub which can be multi-dropped to provide flow control in a plurality of well zones based on control signals through the simple electric line 58. In some applications, the hydraulic actuating fluid may be selectively diverted by the control module 44 to actuate other components in the lower completion 26, e.g. packers, sliding sleeves, or zonal isolation valves. The flow control devices 42 also may comprise various types of plunger assemblies which facilitate return flow through the sand screen assembly joints 43.

Depending on parameters of a given application, the control module 44 may be constructed in a variety of configurations and may comprise various features. Examples of such features include the integral pump 78 and the motor 80 used for hydraulic power generation. The control module 44 also may incorporate or work in cooperation with a pressure compensation system, e.g. compensators 76. In some applications, the control module may comprise or work in cooperation with an accumulator used for storing hydraulic energy. Additionally, electronics 68 may comprise various types of controllers and telemetry systems utilized for communication and for controlling the components of control module 44 and overall flow control system 66.

Other components of the overall well system and multi-zone flow control system 66 also may be adjusted according to the parameters of a given application. The electric line 58 may comprise separate lines for power and data or a combined power/data line. The control system 60 and electric line 58 may be used for carrying a variety of signals along a wholly hardwired electrical communication line or a partially wireless communication line. Such adjustments to the well system may be made according to equipment, environmental, and/or other considerations.

Although a few embodiments of the disclosure have been described in detail above, those of ordinary skill in the art will readily appreciate that many modifications are possible without materially departing from the teachings of this disclosure. Accordingly, such modifications are intended to be included within the scope of this disclosure as defined in the claims.

What is claimed is:

1. A system for use in a well, comprising:
a completion deployed in a lateral wellbore extending through a plurality of well zones, the completion comprising:

a plurality of isolation packers positioned to separate well zones of the plurality of well zones;

a plurality of flow control devices comprising flow control devices in each of the well zones to control flow of fluid from an exterior of the completion to an interior of the completion; and

a control module hydraulically coupled with each of the plurality of flow control devices in each well zone and with a source of hydraulic actuating fluid, the control module being electrically actuated to selectively direct hydraulic actuating fluid to each the flow control devices in selected well zones to enable opening or closing of the flow control devices in the selected well zones, the control module being located along the completion between well zones.

2. The system as recited in claim 1, wherein the completion comprises a sand screen section in each well zone.

3. The system as recited in claim 1, wherein the plurality of flow control devices comprises hydraulically operated plungers selectively shifted by the hydraulic actuating fluid to open or closed positions.

4. The system as recited in claim 1, wherein the plurality of well zones comprises 2-5 well zones.

5. The system as recited in claim 1, wherein the control module is hydraulically coupled with the plurality of flow control devices via hydraulic lines, at least some of the hydraulic lines passing through at least one of the isolation packers.

6. The system as recited in claim 1, wherein the source of hydraulic actuating fluid comprises an actuating fluid reservoir coupled with a pressure compensator.

7. The system as recited in claim 1, wherein the control module comprises a hydraulic pump to pressurize the hydraulic actuating fluid.

8. The system as recited in claim 1, wherein the control module comprises a plurality of solenoid operated valves to control flow of hydraulic actuating fluid to selected flow control devices.

9. The system as recited in claim 1, wherein the completion comprises a plurality of completion joints in each well zone.

10. A system, comprising:

a well completion disposed in a wellbore, the well completion comprising:

a plurality of flow control devices distributed through a plurality of well zones located along the wellbore; and

an electrically controlled module in hydraulic communication with the plurality of flow control devices, the electrically controlled module configured to control flow of the hydraulic actuating fluid to each of the plurality of flow control devices, and the electrically controlled module having a manifold with electrically controlled valves which control flow of hydraulic actuating fluid to selected flow control devices of the plurality of flow control devices.

11. The system as recited in claim 10, wherein the well completion comprises a plurality of sand screen sections having sand screens through which well fluid flows to corresponding flow control devices.

12. The system as recited in claim **11**, wherein the well completion comprises isolation packers positioned to isolate well zones sequentially along the wellbore.

13. The system as recited in claim **12**, further comprising a surface control system coupled to the electrically controlled module via an electric line, the surface control system providing control signals to the electrically controlled module regarding opening and closing of selected flow control devices.

14. The system as recited in claim **13**, further comprising a sensor system positioned along the wellbore to monitor fluid parameters in the well zones.

15. The system as recited in claim **14**, wherein data from the sensor system is processed by the surface control system to facilitate determination as to whether fluid flow into the well completion should be limited in at least one of the well zones.

16. The system as recited in claim **15**, wherein the electrically controlled module is positioned along the well completion with at least one well zone uphole of the electrically controlled module and at least one well zone downhole of the electrically controlled module.

17. A method, comprising:

distributing a plurality of flow control devices along a wellbore completion having sand screen assembly joints;

positioning a control module along the wellbore completion such that flow control devices are disposed in an uphole direction and a downhole direction from the control module;

supplying the control module with hydraulic actuating fluid; and

controlling the control module by electrical signals to direct the hydraulic actuating fluid to selected flow control devices so as to actuate the selected flow control devices between open and closed flow positions, wherein the control module is configured to control flow of the hydraulic actuating fluid to each of the plurality of flow control devices.

18. The method as recited in claim **17**, further comprising using the flow control devices to control the flow of well fluid from an exterior of the wellbore completion to an interior of the wellbore completion.

19. The method as recited in claim **17**, wherein controlling the control module comprises actuating solenoid actuated valves in a manifold of the control module.

20. The method as recited in claim **17**, further comprising locating a group of flow control devices in each well zone of a plurality of well zones along the wellbore completion.
